EDWARD D. SMITH AND REBAH TILLERY SMITH, OF HOUSTON, TEXAS, ASSIGNEES TO
THEODORE E. GUY, TRUSTEE, OF CHICAGO, ILLINOIS.

DEVICE FOR WASHING OIL WELLS.

Application filed April 7, 1919. Serial No. 288,166.

To all whom it may concern:

Be it known that we, EDWARD D. SMITH and REBAH TILLERY SMITH, citizens of the United States, and residents of the city of Houston, county of Harris, and State of Texas, have invented certain new and useful improvements in Devices for Washing Oil Wells, of which the following is a specification.

10 The invention relates to a device for washing, cleaning and sterilizing oil wells, and has for its object the provision of a device which will be durable and efficient in use.

15 A further object is the provision of means whereby the oil sands of an oil well may be thoroughly cleaned and sterilized, and whereby the crystallized paraffin may be quickly and thoroughly removed from the sands of the oil well.

20 Other objects will appear hereinafter.

The invention consists in the combinations and arrangements of parts hereinafter described and claimed.

25 The invention will be best understood by reference to the accompanying drawings forming a part of this specification, and in which,

Fig. 1, represents an oil well showing the invention applied,

30 Fig. 2, represents a cross-section taken on line 2—2 of Fig. 1,

Fig. 3, is a top plan view of a disc,

Fig. 4, represents a top plan view of a disc, secured to the steam pipe.

35 Fig. 5, is a rod secured to the steam pipe, and

Fig. 6, is a top plan view of a washer secured to the lower end of the device.

The preferred form of construction, as illustrated in the drawings, comprises a steam pipe 8, the lower end of which is threaded and adapted to receive an internally threaded annular disc 9, which is beveled on its upper surface. Inserted in the lower end of the pipe 8 is a rod 11, which is bifurcated at its upper end to form the ele-

ments 12 which are securely fastened to the inner lateral walls of the pipe 8 by suitable fastening means 13. The lower end of the rod 11 is threaded, and co-operating with the 50 threaded end thereof is a nut 14' and a locking nut 14. Loosely mounted on the rod 11, and adapted for slidable movement thereon relatively to the disc 9, is a disc 10 which is beveled at its under surface. Positioned 55 loosely on the rod 11, adjacent the lower face of the disc 10, is a washer 17. Positioned on the rod 11, adjacent the washer 17, is a spiral spring 16, the lower end of which engages with a washer 15, which is also loosely 60 mounted on the rod 11. The nut 14' and the locking nut 14 serve to retain these parts in their assembled position on the rod 11.

In operation, a steam boiler is positioned at or near the entrance to the well, to which 65 boiler is connected the pipe 8. The steam in the boiler is carried at a heavy pressure and is conducted into the oil well under heavy pressure.

As is readily apparent, downward pressure 70 on the disc 10 will tend to separate the discs 10 and 9, it being simply necessary that this downward pressure be sufficient to overcome the pressure exerted by the spiral spring 16. It is also evident that the tension of the 75 spiral spring 16 may be increased or diminished, by operating the nuts 14 and 14'. The steam is forced into the pipe 8, and when the pressure in the pipe 8 becomes greater than the pressure exerted by the spiral spring 16, 80 the steam is allowed to escape between the co-operating horizontal faces of the discs 9 and 10, thereby being directed in a horizontal sheet with great force against the lateral walls of the well and at right angles thereto. 85 The force of this steam against the lateral walls of the well will have a tendency to destroy the walls, and the steam itself will be forced back into the oil sands surrounding the walls. Similarly, the solvent which is 90 poured into the oil well and which surrounds the valve constituted by the discs 9 and 10,

will be forced against the lateral walls of the oil well and into the sands surrounding the same. This super-heated steam and the solvent coming into contact with the crystallized paraffin, will dissolve or melt the same. A continuous stream of this paraffin solvent is kept flowing into the oil well while the washing process is taking place, so that the solvent which has become saturated with the 5 paraffin is diluted by the solvent which is being poured into the well, and as the well overflows with the solvent, a solution of paraffin is carried off over the top of the well, so that when the washing process is continued 10 the solution of paraffin which remains in the well will be very weak or greatly diluted. A stream of water is then directed into the well to further weaken or dilute this solvent and carry over the top of the well what little 15 paraffin remains in solution therein.

The principal cause of the clogging of the oil well is the oxidization of the paraffin within the oil sands when the oil is pumped out of the well beneath a certain level. The 20 air entering the well permeates the pores or capillary openings in the oil sands and causes a crystallization of the paraffin therein. This results in a clogging or stopping up of the passages through which the oil is accustomed to flow through the oil sands into the well. When this crystallization has taken place, the well is termed "dead" with the result that the supply of oil which otherwise would be found in the well must be 25 reached by drilling another well in the near vicinity of the "dead" well. By the use of the invention above described, the drilling of this well in the near vicinity of the "dead" well is eliminated.

30 By this device, there is provided a means for thoroughly and efficiently unclogging the passages in the oil sands through which the oil is accustomed to flow, and thereby again restoring free passage to the oil into 35 the well. This device may also be used for the purpose of filling pockets which are formed in constructing a well in which a metallic lining or wall is not used. The metallic wall or lining of the well is frequently omitted, especially when the well is 40 constructed through a rock bed. In constructing such a well however, small fragments of rock are frequently loosened from the sides of the well and it is desirable that 45 these pockets be filled with some material 50 impervious to the oil. To accomplish this, the invention may be used in forcing cement, or other suitable plastic mixture, into the pocket. The cement may be forced through 55 the tubular member 8 and outwardly between the discs 9 and 10.

60 While we have illustrated and described the preferred form of construction for carrying our invention into effect, this is ca-

pable of variation and modification without departing from the spirit of the invention. We, therefore, do not wish to be limited to the precise details of construction set forth, but desire to avail ourselves of such variations and modifications as come within the scope of the appended claims.

Having described our invention, what we claim as new and desire to secure by Letters Patent is:—

1. In an oil well cleaning device, a pipe 75 adapted to conduct steam under pressure into an oil well; a disc secured to and projecting from the periphery of the lower end of said pipe; a disc slidably mounted on a rod secured to said pipe; and adapted to cooperate with said first named disc for emitting the cleaning fluid laterally against the walls of the well and means for normally holding said discs in close engagement with each other, substantially as described. 80

2. A device of the class described, comprising a tubular member adapted for insertion into a well; a stem secured to the wall of said member adjacent one end thereof; and means adjacent said end of said member for directing material forced therethrough in a lateral sheet against the wall of said well, said means comprising a pair of co-operating horizontal discs, one of which is slidably mounted upon said stem, the 95 other of which is fastened to said tubular member substantially as described.

3. A device of the class described comprising a tubular member insertible in a well, one end of said member being open; a disc exteriorly threaded to said member adjacent said end; a stem directly attached to the wall of said member; and a disc slidably mounted on said stem and adapted to engage said open end and said first mentioned disc 100 for closing said end of said member, substantially as described. 105

4. A device of the class described comprising a tubular member insertible in a well, one end of said member being open; a disc secured exteriorly to said member adjacent said end; a forked stem directly attached to the wall of said member; a disc slidably mounted on said stem and adapted to engage said first mentioned disc for closing said end 110 of said member; and resilient means on said stem for normally retaining said slidably mounted disc in closing position, substantially as described. 115

5. A device of the class described comprising a tubular member insertible in a well, a stem having forks secured directly to the inner wall of said member adjacent one end; and a spring-held closure for said end slidably mounted on said stem, substantially as 120 described.

6. A device of the class described comprising a tubular member insertable in a

well, one end of said member being open; a disc exteriorly threaded to said member adjacent said end; a forked stem directly attached to the wall of said member; and a disc slidably mounted on said stem and adapted to engage and co-operate with said first mentioned disc to close said opening, the co-operating faces of said discs extending horizontally for emitting steam in a lateral sheet against the walls of the well.

10 In testimony whereof we have signed our

names to this specification in the presence of two subscribing witnesses.
